UNITED STATES PATENT OFFICE

PAUL V. KINNEY, OF AUSTIN, COLORADO, ASSIGNOR TO MACINTYRE-FISHBACK MFG. CO., OF PUEBLO, COLORADO, A CORPORATION OF COLORADO

FRUIT-PICKING BAG

Application filed November 17, 1928. Serial No. 320,160.

This invention relates to a fruit picker's garment and has special reference to a garment to be worn by a fruit picker and into which fruit may be gathered, the garment being provided with means whereby the gathered fruit may be allowed to fall from the garment into a basket or other suitable receptacle.

One important object of the invention is to improve the general construction of devices of this character.

A second important object of the invention is to provide a blouse like garment adapted to be put on over the wearer's head and provided at the neck portion with means to hold the front of the neck tightly spaced from the body while the waist portion is provided with gathering means so that the bottom of the garment may be gathered tightly around the waist and thus hold the fruit dropped in through the neck.

A third important object of the invention is to provide a garment of this description with a chute or delivery end leading from the waist at the bottom of the bloused portion and means to normally hold the chute elevated to prevent the escape of fruit therefrom.

With the above and other objects in view as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

Figure 1 is a perspective view of a man wearing the improved garment.

Figure 2 is a front view of the garment.

Figure 3 is a section on the line 3-3 of Figure 2.

Figure 4 is a front view of the garment with the chute dropped.

Figure 5 is a section on the line 5-5 of Figure 4, the lower edge of the garment being bloused upwardly.

In the construction of this garment there is provided an upper front portion 10 having

a downwardly extending strip 11 which forms the front of the delivery chute. This front portion is cut away to provide the neck opening 12 and the shoulder pieces 13 which unite with the shoulder pieces 14 of the back 15. The top of the neck portion is turned under and stitched as shown as 15' to the underside of the front portion and in the fold thus formed there is inserted a rope or other stiffening means 16 which stiffens the front of the neck and tends to hold it away from the body of the wearer. Reinforcing straps 17 run over the shoulders and between the front and back portion below the arm hole are side gores 18. Secured to the front edges of the side gores and to the lateral bottom edge portions of the front 10 is a lower front portion 10 formed in two halves united by stitching 20, these halves being connected at their sides to the tube front 11. The lower edges of the portions 19, 18 and 15 are doubled and sewed to provide a tubular passage 21 for a draw string 22 by which the bottom of the garment may be tightly gathered around the waist of the wearer. On each of the tube portions 19 in spaced relation to the end of the tube is a tab 23 carrying a button 24 adapted to be engaged by a fastening loop 25 carried on a tab 26 swinging from the respective reinforcing strip 17.

By an inspection of Figures 2 and 3 it will be seen that when gathering the fruit the tubular portion or delivery spout is doubled up, the lower end being turned up forwardly to lie against the upper part and then the entire spout being turned up to lie against the front 10 as clearly shown in Figure 3. The members 25 are now engaged on the button 24 and the delivery spout will be held in its raised position. The person wearing the garment may now gather the fruit, dropping it down the neck portion until the blouse is filled to the extent desired. He then goes to the proper place for delivery, unhooks the members 25 and lowers the delivery spout by unfolding the same forwardly into the receptacle intended to receive the fruit. By properly manipulating the spout the fruit may be allowed to roll gently down without bruising or other damage and after the fruit

has all been delivered the spout is again folded up and the wearer proceeds to gather a fresh supply of fruit.

There has thus been provided a simple and efficient device of the kind described and for the purpose specified.

It is obvious that minor changes may be made in the form and construction of the invention without departing from the material spirit thereof. It is not, therefore, desired to confine the invention to the exact form herein shown and described, but it is desired to include all such as properly come within the scope claimed.

Having thus described the invention, what is claimed as new, is:

A fruit gathering garment including a body forming a blouse and provided with means for gathering the lower edge closely about the body of the wearer, a delivery tube extending from the lower front portion of the body and foldable forwardly and upwardly against the front of the body, buttons on the underside of said tube to lie in front of the tube upon the latter being folded upwardly, and tabs depending from the shoulder portions of the blouse and carrying loops engageable with said buttons.

In testimony whereof I affix my signature.

PAUL V. KINNEY.
